(57) CLAIM

The ornamental design for a set of packages for deviled eggs, as shown and described.

DESCRIPTION

FIG. 1 is a top plan view of the set of packages for deviled eggs of the present invention;

FIG. 2 is a front view thereof;

FIG. 3 is a rear view thereof;

FIG. 4 is a left side view thereof;

FIG. 5 is a right side view thereof;

FIG. 6 is a bottom plan view thereof; and,

FIG. 7 is a perspective view of the set of packages for deviled eggs of the present invention illustrating an individual utilizing the egg yolk mixture container to fill hard boiled egg white halves with egg yolk mixture.

The broken lines shown in the Figures are for illustrative purposes only and form no part of the claimed design.

1 Claim, 2 Drawing Sheets
